UNITED STATES PATENT OFFICE

2,467,242

MEANS FOR REPRODUCING DIAGRAMS,
DESIGNS, AND THE LIKEWilliam Swartz, Chicago, Ill., assignor to Embosso-
graf Company of Illinois, a partnership

Application July 15, 1943, Serial No. 494,882

4 Claims. (Cl. 164—29)

1

The invention relates to the art of reproducing diagrams, designs and the like and is particularly concerned with a novel method of, and means for reproduction of designs, diagrams and in general any representation of ornamental or educational nature.

In the graphic arts the reproduction of designs or diagrams was hitherto carried out by producing a drawing of such design and thereafter a single die was produced which formed a replica of the desired design. In this method it is necessary to produce an individual die for each and every design entailing a high cost and considerable time for producing such dies.

The present invention deals with the reproduction of designs and the like obviating the necessity of producing drawings to serve as patterns and obviating the necessity of making up unit dies especially of complicated and large diagrams.

It is one of the principal objects of the invention to provide a plurality of die sections or elements which can be assembled to form a single die defining the desired design or diagram and which segments can be re-arranged in many ways to produce varieties of designs.

It is a further object of the invention to secure the die segments in assembled relation so as to obtain the same reproduction as if a unit die had been used.

Another object constitutes the provision of die segments which when assembled and brought to bear on the printing or engraving material under pressure leave an imprint of a continuous and uninterrupted nature the same as if a unitary die had been used.

It is also an object to provide certain features of construction and assembly tending to enhance the utility and efficiency of the invention.

With these and other objects in view which will become apparent from a perusal of the invention, the latter comprises certain steps in a novel method and means for carrying out such method as described in the following specifications, particularly pointed out in the claims forming a part thereof, and illustrated in the drawings, in which:

Fig. 1 is a top plan view of a die segment constructed in accordance with my invention.

Fig. 2 is a side view of the die segment.

Fig. 3 is a section on the line 3—3 of Fig. 2.

Fig. 4 is a top plan view of a variant form of die segment.

Fig. 5 is a section on the line 5—5 of Fig. 4.

2

Fig. 6 is a top plan view of a circular die element.

Fig. 7 is a section on the line 7—7 of Fig. 6.

Figs. 8 and 9 are top plan views of other variants of die elements.

Fig. 10 shows in top plan view a plurality of die elements in assembled relation for representation of a diagram.

Fig. 11 shows a portion of the diagram in an enlarged scale.

Fig. 12 is an enlarged section on the line 12—12 of Fig. 10.

Fig. 13 is a fragmentary perspective view to illustrate a step in carrying out my process.

Fig. 14 is a perspective view of a special paper employed in the method, and

Fig. 15 is an enlarged section on the line 15—15 of Fig. 13.

The invention is illustrated in connection with the reproduction of diagrams which is of course only indicative of the principle involved and may be applied to the reproduction of any representation where speed and inexpensiveness is of importance. The principle referred to involves the provision of die-elements or sections of various shapes or forms which may be assembled in any desired manner to assume a desired design and such assembled elements may be used as a unit for obtaining impressions to provide replica of such desired design.

The word design is used to indicate any representation either of an ornamental, technical or educational nature.

Referring to the various views in the drawing, 35 10 designates a die-element which comprises a base 11 of rectangular cross section which is integral with a synclined top or head 12 of less width at the base than the base 11 so as to define shoulders 13 and 14. The top face of the head 12 is grooved with angular side walls to define cutting edges 15 and 16.

Attention is called to the fact that in each element the head and the cutting edge are of the same length as the base so that when two die elements are placed endwise in abutting relation as shown in Fig. 10 at 17, then the cutting edges are in contact, so that an impression made with these cutting edges is continuous and no break appears even though the die is not unitary but made up of elements.

Where elements are placed at right angles to each other it is also necessary to have the cutting edge in contacting relation. To this end the die-element 10 is cut away as at 18 and 19 so that 55 the inner wall of the cut out portion or recess

(Fig. 3) is in vertical registry respectively with the cutting edges 15 and 16. The die element 21 having cutting edges 22 when arranged to fit with one end in the recess of element 10 provides for a contacting relation of its cutting edges 22 with the edge 16 of element 10. Thus again an impression made with these elements will show no break between the lines produced by edges 22 and 16 and thus gives rise to the impression that a unitary die was used.

The angular element 23 has cutting edges 24 which extend the entire length of the element.

The circular die element 25 is provided with circular cutting edges 26, which are flush with the sides of the element.

The die-element 27 representing letter A shown in Fig. 9 has likewise cutting edges 28 co-terminous with the base of the element.

No attempt has been made to show all of the varieties of elements to be used and only a few instances have been illustrated.

In Fig. 10 a number of elements are assembled to produce a diagram such as used to denote a radio circuit.

As indicated in Fig. 12 a platform 30 is placed on the lower part of a press 34 and a sheet of chart paper 31 superposed by a layer 32 of translucent wax is arranged on said platform.

On such layer of wax the elements are arranged to form the diagram shown in Fig. 10 and are held in assembled relation by the wax the squares of the chart paper aiding in arranging the elements in proper position.

On the assembled elements is placed a sheet of paper 33 which on the upper side is covered with a thermoplastic pressure-sensitive adhesive 35.

The other side of the paper may be covered with a layer 36 zinc sulphide or strontium sulphide which has luminescent properties. Over the paper is arranged a cardboard 37. When the lower part 34 of the press is brought up then the cutting edges of the die element will cut out from the paper 33 strips forming a replica of the diagram shown in Fig. 10. The surplus paper not used in producing the diagram is then removed.

Thereupon the strips as shown in Fig. 13 are subjected to the influence of an iron 38 whereby the adhesive is heated and cements the strips to the cardboard 37.

The paper 33 may be of any desired color or design or many colors and where portions of the diagram are to have different colors, then additional sheets or strips of paper 39 may be used in some portions of the diagram or design, as shown in Fig. 15. The employment of different colors for portions of the design meets a long felt need since it enables the reproduction of color codes.

It is, of course, understood that the cutting edges of the die elements are in the same horizontal place so that even cutting is ensured.

The invention has been shown to illustrate the principle underlying the same.

Numerous changes and modifications may be made without departing from the spirit of the invention. I, therefore, do not limit myself to the sequence of steps enumerated in the method, nor to the particular construction of elements shown, but claim my invention as broadly as the state of the art permits.

I claim:

1. A device for reproducing designs and the like from strips of material comprising an assortment

of die elements of various shapes capable of being selectively assembled to simulate a desired design, each die element having spaced parallel forming edges capable of intimate contacts with the forming edges of an adjacent element, said elements being assembled end to end some of said elements being constructed to permit the forming edge of an angularly disposed element in abutting intimate relation to the forming edge 10 of the adjacent element and at angles to each other in conformity with a desired design, and means for automatically holding said elements in assembled relation during the stamping operation resulting in impression having a continuity of lines as produced by unitary dies.

2. A device for reproducing designs and the like from strips of material comprising an assortment of die elements of various shapes capable of being selectively assembled to simulate a desired design, each die element having spaced parallel forming edges coextensive with said element to provide intimate contact between edges of abutting elements, said elements being assembled end to end and at angles to each other in conformity with a desired design, the elements adjacent to the angularly disposed elements having cut-away portions to permit the angular elements to be partly received therein so that the forming edges of both elements are in abutting intimate relation, and means for automatically holding said elements in assembled relation during the stamping operation resulting in impressions with continuous, uninterrupted lines.

3. A device for reproducing designs and the like from strips of material, including an assortment of die elements of various shapes assembled in a single plane, to produce any desired design, each die element having spaced parallel cutting edges extending the full length of said element to intimately contact the parallel cutting edges of an adjacent element, some of said elements being assembled end to end and other of said elements having cut-away portions to permit angular abutting relation thereto of an element with its cutting edges in intimate contact with the cutting edges of said other element to form the desired design, and means for holding the said elements in assembled relation during the stamping operation whereby the impression produced has continuity of lines free from spacings as obtained by the use of unitary dies.

4. A device for reproducing designs and the like from strips of material comprising an assortment of elements of various shapes assembled to produce the desired design, each die element having spaced parallel cutting edges extending the full length of said element, some of said elements being assembled end to end with their cutting edges in intimate contact and other elements being assembled in angular relation to each other, one of the elements at each angular relationship having a right angular notch cut therein with its end coincident with one of the cutting edges of the notched element, the other element of the angular relationship being inserted in said notch with the cutting edges in abutting intimate relation to said cutting edge of the notched element, means to hold all said cutting elements in design formation during cutting whereby the resulting design is produced with continuity of lines free from spacings as would be obtained with a unitary die of like shape.

WILLIAM SWARTZ.
